(57) **CLAIM**

The ornamental design for a cable management installation tool, as shown and described.

DESCRIPTION

FIG. 1 is a perspective view of cable management installation tool showing my new design;

FIG. 2 is a front view thereof;

FIG. 3 is a side view thereof;

FIG. 4 is a top view thereof; and,

FIG. 5 is a perspective view thereof in use with optional cable tube and cables, with elements in dashed lines forming no part of the claimed design.

1 Claim, 5 Drawing Sheets(56)
